UNITED STATES PATENT OFFICE.

THOMAS WRIGHT, OF JERSEY CITY, NEW JERSEY.

COAL-WAGON.

1,019,211.

Specification of Letters Patent.

Patented Mar. 5, 1912.

Application filed August 5, 1910. Serial No. 575,744.

To all whom it may concern:

Be it known that I, THOMAS WRIGHT, a citizen of the United States, residing at Jersey City, in the county of Hudson and State of New Jersey, have invented a new and useful Coal-Wagon, of which the following is a specification.

This invention relates generally to wagons and particularly to the type used for carrying coal and other similar material.

One of the objects of the invention is to provide improved means for elevating the body of the wagon above the truck thereof when it is desired to discharge the contents down a chute or incline.

A further object of the invention is to provide a wagon body having movable bottom sections which can be elevated at one side so as to cause them to act as inclines and thus automatically discharge the contents of the body of the wagon into the chute which is to convey them to the sidewalk or other points of delivery.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of the claims without departing from the spirit of the invention.

In the accompanying drawings forming part of this specification, Figure 1 is a side elevation of a coal wagon constructed in accordance with the present invention. Fig. 2 is a view similar to Fig. 1 showing the body of the wagon raised above the truck thereof, and illustrating particularly the shape of the wheeled lifting arms, a portion of the side of the body of the wagon being broken away so as to show one of the bottom sections in raised or inclined position. Fig. 3 is an end elevation looking at the rear of the wagon with the body thereof raised above the truck, a portion of the rear end of the wagon being broken away in order to show one of the bottom sections in raised position. Fig. 4 is a detail view in under plan of one of the sets of lifting arms. Fig. 5 is a diagrammatic view showing one of the curved lifting arms in an intermediate position. Fig. 6 is a side elevation of a wagon equipped with

a slightly modified arrangement of lifting levers.

Like reference numerals indicate corresponding parts in the different figures of the drawings.

The coal wagon of the present invention is provided with front wheels 1 having a lower bolster member 2 connected therewith and coöperating with an upper bolster member 3. Rear wheels 4 serve to support the rear bolster 5. Supported upon the bolsters 3 and 5, as shown in Fig. 3 of the drawings is a truck bottom 6 which is provided with longitudinally extending side plates or sills 7 on which the body 8 of the wagon rests when it is in lowermost position.

For the purpose of guiding the wagon body 8 in its vertical movement, said body is provided with depending vertical arms 9 which are bifurcated at their upper ends as shown in Fig. 1 and suitably bolted at 10 to the wagon body. The lower portions of said guiding arms 9 extend slidably through brackets 11 bolted at 12 upon the sills or side plates 7 of the wagon truck.

The means for raising and lowering the wagon body 8 upon the truck of the wagon preferably includes a plurality of curved lifting arms 14. Each of the lifting arms 85 is pivotally connected at 15 at its upper end to a pair of parallel links 16, shown best in Fig. 4 of the drawing. Each pair of parallel links 16 is pivotally mounted at 17 upon a bracket 18 bolted or otherwise suitably secured at 19 to the bottom of the wagon body. At its lower end, each of the curved lifting arms 14 has journaled thereon at 20 a roller or anti-friction device 21 preferably in the form of a grooved wheel as shown in Fig. 95 3, the wheels 21 being connected with each other in pairs, by means such as the axles 23. It will thus be seen that each arm is movable bodily relative to both the wagon body and the truck whereas structures heretofore devised and which employ lifting arms, have had the arms pivotally connected either to the body or to the truck. The grooved wheels 21 run upon tracks 24 which are suitably supported upon the bottom 6 of the truck of the wagon. The tracks 24 as clearly indicated in Fig. 2 of the drawing, are dipped or depressed at their forward and rearward ends.

The means for causing the pairs of rollers 110

21 to be moved toward each other on the tracks 24 so as to elevate the wagon body 8 preferably includes a pinion 30 mounted on a squared shaft 31 and meshing with a large 5 gear wheel 32 fixed on a shaft 33. Also fixed on the shaft 33 is a pinion 34 which meshes with a large gear wheel 35 fixed on a shaft 36. The shaft 36 at its center has fixed thereon one or more winding drums 37 10 as shown in Fig. 3 on which are wound chains 39 which extend around wheels 40 mounted on the shafts 23 of the wheels 21 and are fixed or otherwise suitably secured at 41 to the truck body. By winding on the 15 squared shaft 31, the chains 39 are wound onto the drum 37 so as to draw the pairs of wheels 21 toward each other and thus elevate the wagon body 8 as shown in Fig. 2 of the drawing.

20 It is to be particularly noted from Fig. 5 of the drawing, that the curved lifting arms 14 have a very important function in elevating the wagon body. When the wagon body is loaded and in its lowermost 25 position, if the lifting arms 14 were straight, the strain thereon, on account of the acute- ness of the angle at which they lie to the bottom of the wagon body 8, would render it almost impossible to place enough power 30 or purchase on the arms 14 to lift the wagon body 8 without fracturing said arms. By employing the curved lifting arms 14 in combination with the links 16, the arms 14 roll against the bottom of the wagon body 8 35 as shown in Fig. 5 in the manner of cams and thus in effect decrease the active length of the arms, when the wagon body is first being lifted, to a distance approximately equal to the distance from the center of the 40 wheels 21 to that point on the bottom of the wagon body 8 with which the curved portions of the arms 14 contact. The lifting arms 14 thus produce the effect of gradually lengthening lifting members as the wheels 45 21 are drawn toward each other into the position illustrated in Fig. 2.

The wagon body 8 is divided into four compartments by means such as the partitions 45 in Fig. 2 and each of these compartments is provided with a bottom 46 which is hinged or pivotally mounted along one longitudinal side edge thereof as indicated at 50 47 and is provided at the opposite edge with an eye or attaching member 48 to which is secured a chain 49. The chain 49 extends upward over a pulley 50 journaled upon a bracket 51 which is secured to the upper edge of the wagon body. The outer end of the chain 49 is secured at 53 to a handle lever 54 which is fulcrumed at 55 upon a bracket 56 55 secured to the outside of the wagon body. The handle lever 54 is provided with a hand grip 57 by means of which it can be drawn downward into the position illustrated by 60 one of the levers in Fig. 2 so as to lift the 65

bottom 46 into the inclined position shown in Fig. 3 of the drawings. The coal is thus caused in an automatic manner to flow outward through the member 63 into the telescopic chute 60 which is normally folded 70 within the bracket 61 as shown in Fig. 2 of the drawings. The member 63 and the chute 60 can be arranged opposite the door to any one of the four compartments.

The coal wagon of the present invention 75 is strong, simple, durable and comparatively inexpensive in construction as well as thoroughly practical, efficient and economical in use.

In the modified construction shown in Fig. 6, the curved lifting arms 14' connected at 15' with the links 16' are further equalized in their actions by means of links 80 which are pivotally secured at 81 to the wagon truck and at 82 to the arms 14'. In 85 all other respects the construction and operation are the same as previously described and illustrated.

What is claimed as new is:

1. A wagon including a truck element, oppositely disposed similar cam-shaped arms supported thereby, a body element supported at all times solely by the arms, pivoted connections between the arms and the body element, and means for shifting the arms along the truck element to roll the oppositely disposed arms simultaneously upon the body element.

2. A wagon including a truck element, a body element, oppositely disposed similar cams interposed between said elements and constituting the sole supports for the body element at all times during the elevation of said element, means for shifting the cams bodily along one of said elements to roll them simultaneously upon the other element, and connections between the cams and the last mentioned element.

3. A wagon including a truck, oppositely disposed similar arms mounted thereon and having curved bearing faces, a body mounted on and supported solely by said faces at all times during the elevation of the body, connections between the arms and body, and means for bodily shifting the arms simultaneously along the truck and relative to each other to roll the arms upon the body.

4. A wagon including a truck, oppositely disposed cam shaped arms supported thereby, a body bearing on and supported by the arms at all times during the elevation of the body, connections between the arms and body, and means for simultaneously shifting the arms toward or away from each other on the truck to roll the arms upon the body.

5. A wagon including a truck, a body, cam-shaped arms supported by the truck and having convexed bearing faces engaging the body at all times during the elevation of the body and constituting the sole support.

thereof, link connections between the arms and body, and means for bodily shifting the arms toward or from each other upon the truck.

- 5 6. A wagon including a truck, oppositely disposed cam-shaped arms supported by the truck, a body bearing downwardly upon the convex faces of the arms at all times during the elevation of the body, pivoted elements
10 constituting the sole connections between the body and arms, and means for shifting the

lower ends of the arms upon the truck and relative to each other to roll the arms upon the body.

In testimony that I claim the foregoing 15 as my own, I have hereto affixed my signature in the presence of two witnesses.

THOMAS WRIGHT.
